ATTORNEY.

UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

ADJUSTABLE CONDENSER

Application filed February 11, 1929. Serial No. 339,144.

My invention relates to adjustable condensers in general and more particularly to condensers employed in high frequency electrical signaling systems.

5 An object of my invention is to provide an adjustable condenser wherein the capacity is controlled easily and accurately within desired limits.

Another object of my invention is to provide 10 an adjustable condenser capable of withstanding high voltages.

Still another object of my invention is to provide 15 an adjustable condenser wherein extraneous electrostatic fields are eliminated from the condenser when such condenser is employed in high power, high frequency transmitters.

Other and further objects of my invention 20 are to provide certain structural features whereby the efficiency of an adjustable condenser for high frequency, high power transmitters is increased.

A better understanding of my invention 25 can be had from the specification following and from the accompanying drawing, wherein:

Figure 1 illustrates a front elevation in 30 part section of the adjustable condenser of my invention; Fig. 2 illustrates a side elevation in part section of the adjustable condenser of my invention; and Fig. 3 shows a view in section of the upper plate structure taken on the lines 3—3 of Fig. 1.

Adjustable condensers employed in high 35 power and high frequency transmitters must be of the design capable of withstanding very high voltages. Such condensers must be adjustable over wide limits of capacity. In addition, the insulation of the condenser must 40 be such as to withstand the strain of very high frequencies. The metallic capacity plates must be of low resistance and capable of carrying large values of current without appreciable loss. A further desirable feature 45 is that the condenser be shielded from extraneous electrostatic fields which are present in high power transmitters operating at high frequencies. My application, Serial No. 327,990, filed December 22, 1928, shows a condenser similar to that described herein; the

present adjustable condenser providing certain features of improvement.

Figure 1 of the accompanying drawing shows a front elevation in part section of the adjustable condenser of my invention. Adjustable plate structures 11 and 12 are electrically connected together and in combination constitute one capacity plate of the condenser. Plate structures 11 and 12 are of suitable metal such as brass or aluminum.

A convenient form of construction for plate structure 11 is shown in Fig. 1. Two vertical end members 7 of approximately rectangular section have their outer corners well rounded and on their inner faces are recessed to form a shoulder portion as shown in Fig. 3. A bore 10 is provided in each end member to receive actuating shaft 15. A plate 8 is bent in the shape of an inverted U forming two vertical sheets closed on top by a curved portion which is the base of the U. The edges of each sheet fit into the shoulder recesses of end members 7 and are riveted or bolted thereto. The interior of the U between end members 7 is therefore hollow and open below. The lower plate structure 12 may consist of a sheet folded about a form such that it will take the form similar to that of the upper plate and having its bottom closed by base member 4. There is a connection between the lower plate and the upper due to the resiliency between the two plates. The sheets constituting plate structures 11 and 12 may conveniently approximate a parallel relationship.

Plate structure 12 is of slightly larger dimensions than plate structure 11, the former adapted to slide over the latter. The sliding movement of structure 12 over the surface of structure 11 is accomplished by the action of a threaded shaft 15 engaging with a threaded bore in tube 5. Tube 5 is secured to plate structure 12 by means of a pin or screw 6. Tube 5 moves vertically through bore 10 in plate structure 11. Shaft 15 rests in suitable bearings provided in member 14. Member 14 supports gear mechanism 18, 19, 20, 21 and shafts 16 and 22. Shaft 15a operates in a manner similar to the operation of shaft 15 and serves to divide the lifting force

100

between different portions of plate structure 12. Shafts 15 and 15a are turned by means of bevel gears 18, 19, 20, 21 and shafts 16 and 22. Supporting member 14 and plate structure 11 are held together in spaced relationship by tubular member and bolt 17. The adjustable plate structures 11 and 12, together with the adjusting mechanism are supported by insulating members 26. Insulating members 26 may be in turn supported by the main framework of the transmitter. To prevent complete separation of plate structures 11 and 12 some type of stop is necessary. To restrict the movement of plate structure 12 within desired limits I provide a rod 1 extending the height of plate structure 12 on the interior thereof.

One end of rod 1 is threaded and engages in base member 4. The upper end of rod 1 is provided with a head 1a. A block 2 of suitable material is secured to the interior wall of plate structure 11 by means of screws 3. The head 1a of rod 1 passes through part 2 for a limited distance but is prevented from disengagement therefrom. The other capacity plate of the condenser is supplied by plate member 30, shown in section. Plate member 30 comprises a partly flattened metallic cylinder or compartment the walls of which are held in spaced relationship with respect to plate structures 11 and 12 and insulated therefrom. Plate member 30 may be in the form of a box entirely enclosing plate structures 11 and 12. It is desirable to arrange this box so that it will have sides approximately parallel to plate structures 11 and 12. Plate member 30 is supported on insulating members 25 which are in turn supported from the main framework of the transmitter. The socket for retaining the anode of a liquid cooled thermionic tube may be positioned in the space 31 and supported by member 40. The anode of the tube would be, in this instance, connected electrically to plate member 30. Certain details of the stop employed for restricting the downward movement of plate structure 12 are more fully illustrated in Fig. 2 of the accompanying drawing. Reference characters corresponding to those employed in Fig. 1. Plate structures 11 and 12 are illustrated with broken away sections to more clearly show this feature. The effective capacity area of plate structures 11 and 12 is adjustable by means of sliding plate structure 12 over plate structure 11. The sliding movement is obtained by the threaded stud and bore shown in Fig. 1. A part 2, such as a block of insulating material or metal, is secured to the inner walls of plate structure 11 by means of screws 3.

A vertical bore partly through member 2 serves as a guide for rod 1. Near the lower edge of part 2, the diameter of the bore is reduced, from approximately that of the

head 1a to that of the body of rod 1. This prevents head 1a from entirely disengaging from part 2 and since rod 1 is secured to the base 4 of plate structure 12, prevents excessive downward movement of plate structure 12.

Many advantages appear from the arrangement employed in the adjustable condenser system of my invention. The structure is such as to provide a highly efficient condenser for use in electrically balanced circuit arrangements of high frequency transmitting systems. A maximum air insulation area is provided and the insulating material employed is placed in such positions where the electrostatic fields are of minimum intensity. The losses experienced when insulating materials are employed, both electrically and mechanically, make the arrangement of my invention superior to types of high power, high frequency adjustable condensers heretofore employed. Any number of plate structures similar to members 11, 12 and 30 may be employed. Any number of plates either electrically connected in common or insulated from each other may be adjustably controlled by a common mechanical means.

I realize that many modifications of my invention are possible and it is to be understood that my invention shall not be limited by the foregoing specification or by the accompanying drawing but only by the scope of the appended claims.

What I claim as new and desire to secure by Letters Patent of the United States is as follows:

1. An adjustable condenser comprising in combination a plurality of plate structures having faces substantially mutually parallel and adapted to telescope the one over the other, a threaded rod in one of said plate structures engaging with a threaded bore provided in another of said plate structures for adjusting the relative position of said plate structures, a traveling rod member associated with said first named plate structure movable through a restricted bore therein for restricting the relative movement of said plate structures, and a stationary outer conductive plate structure having faces substantially parallel to faces of said first mentioned plate structures, said outer plate structure being maintained in spaced and insulated relationship from said first mentioned plate structures.

2. An adjustable condenser comprising in combination a plurality of plate structures electrically connected together and slidably positioned one over the other, means for causing the sliding movement of said plate structures with respect to each other, means for restricting such sliding movement to prevent disengagement of said plate structure and a stationary outer plate structure spacially

positioned and electrically insulated from said first mentioned plate structures.

3. An adjustable condenser comprising in combination a plurality of conductive plate structures slidably positioned one over the other, means for actuating the sliding movement of said plate structures with respect to each other, said means comprising a threaded rod in one of said plate structures coacting with a threaded bore contained in another of said plate structures, means for restricting such sliding movement to prevent disengagement of said plate structures, and an outer stationary plate structure maintained in spaced relationship with respect to said first mentioned plate structures and having faces substantially parallel to faces of said first mentioned plate structures.

4. An adjustable condenser comprising in combination a plurality of conductive plate structures slidably positioned one over the other, means for actuating the sliding movement of said plate structures with respect to each other in balanced relationship, said means comprising a plurality of rotatable rods cooperatively actuated and attached to one of said plate structures and having a threaded portion coacting with threaded bores in another of said plate structures, means for restricting such sliding movement to prevent disengagement of said plate structures, and an outer stationary plate structure maintained in spaced relationship with respect to said first mentioned plate structures and having faces substantially parallel to faces of said first mentioned plate structures.

5. In a condenser system, a pair of plate structures having faces substantially mutually parallel and adapted to telescope the one over the other, one of said plate structures comprising two supporting members and a conducting sheet comprising a pair of parallel flat portions each attached to and joining said supporting members, a threaded rod in one of said plate structures engaging with a threaded bore provided in the other of said plate structures for adjusting the relative position of said plate structures, a traveling rod member associated with said plate structures movable through a restricted bore therein for restricting the relative movement of said plates, and a stationary outer conductive plate structure having faces substantially parallel to faces of said first mentioned plate structures, said outer plate structure being maintained in spaced and insulated relationship from said first mentioned plate structures.

6. In a condenser system, a pair of plate structures having faces substantially mutually parallel and adapted to telescope the one over the other, one of said plate structures comprising two supporting members, a U-shaped plate member closed at the end opposite said other plate structure and open at

the end adjacent thereto, said U-shaped member having its parallel sides attached to and joining said supporting members, a threaded rod in one of said plate structures engaging with a threaded bore provided in the other of said plate structures for adjusting the relative position of said plate structures, a traveling rod member associated with said plate structures movable through a restricted bore therein for restricting the relative movement of said plate structures, and a stationary outer conductive plate structure having faces substantially parallel to faces of said first mentioned plate structure, said outer plate structure being maintained in spaced and insulated relationship from said first mentioned plate structures.
